Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a bottom view of a shoe showing my new design; FIG. 2 is a bottom front perspective view thereof; and, FIG. 3 is a bottom rear perspective view thereof.

The broken lines immediately adjacent to the shaded areas represent the bounds of the claimed design and form no part thereof. The broken lines within the shaded area form no part of the claimed design. The broken lines depicting the remainder of the shoe form no part of the claimed design.
